UNITED STATES PATENT OFFICE.

JOHN B. BARTHOLOMEW, OF PEORIA, ILLINOIS, ASSIGNEE, BY MESNE ASSIGNMENTS,
TO AVERY COMPANY, A CORPORATION OF ILLINOIS.

TRACTION-ENGINE.

1,116,785.

Specification of Letters Patent.

Patented Nov. 10, 1914.

Application filed August 7, 1907, Serial No. 387,539. Renewed March 9, 1914. Serial No. 823,615.

To all whom it may concern:

Be it known that I, JOHN B. BARTHOLOMEW, a citizen of the United States, residing at Peoria, in the county of Peoria and State of Illinois, have invented certain new and useful Improvements in Traction-Engines, of which the following is a specification, reference being had therein to the accompanying drawing.

10 This invention relates to improvements in traction engines; more particularly to engines of the class in which the cylinders, pistons, and the shafting and gearing are all placed below the boiler. Heretofore, engines 15 of this sort have been constructed with heavy, cumbersome and expensive frame structures situated in relatively low horizontal planes, these extending from end to end and having combined with them extension 20 frames projecting forward beyond the front end of the boiler and beyond the front end of the main frame. As is well known, it is very desirable to have these traction engines as light as possible, without sacrificing 25 strength or rigidity, in order that they may be taken into places and over ground which cannot be traveled over when they are heavy.

30 The purpose of the present invention is to provide a strong engine structure without employing the heavy beam frames that have been heretofore used and which will permit the use of all of the necessary engine parts, shafting and gearing, without requiring that 35 they should be attached to the boiler, and also permit the use of front ground wheels so arranged that they can be turned under the boiler for steering.

40 The invention relates to other matters which will be readily understood from the description below, taken in connection with the drawing.

Figure 1 is a side view of a traction engine embodying my improvements. Fig. 2 is a top plan view of the parts remaining after the boiler, the fire-box and the cab have been removed. Fig. 3 is a vertical transverse section on the line *a*—*a* of Figs. 1 and 2. Fig. 4 is a vertical transverse section on the line *b*—*b*, Figs. 1 and 2. Fig. 5 is a perspective of the front bracket connected to the front wheels. Fig. 6 is a perspective of the engine supporting bracket. Fig. 7 is a perspective of the bracket at the center of the boiler.

In the drawings many of the parts of a

traction engine are indicated more or less conventionally, and with respect to these it will be understood that the constructor can employ one form or another as he prefers.

A indicates, generally, the boiler proper; B the fire-box; C the cab; D the rear ground wheels; E the front wheels; F the engines proper; and G the crank shaft.

At H, I there is intermediate shafting and gearing which may be of any preferred sort including means for changing speed and means for compensating in the application of power and motion to the ground wheels, respectively.

J indicates a short frame having on each 70 side the lower bar *j* and the upper bar *j'*. This frame extends from points in the rear of the axis of the rear ground wheels to the crank shaft G, which is mounted upon the front end thereof in bearings at *g*. 75

K, K indicate stay rods or supporting rods which are interposed between the forward part of the frame J and the boiler. They are firmly secured in brackets at *k* secured to the frame and in brackets *k'* secured to the underside of the boiler; and in order to compensate for strains these rods K may be provided with means for adjusting them longitudinally so as to maintain a firm and proper bracing of the boiler and the frame 85 with relation to each other.

L indicates, as an entirety, a bracket which extends downward from the boiler at points nearer its front end. It is formed with a concave saddle *l* for the boiler and fits 90 snugly against the under side thereof. From this there extend downward and laterally the legs *l'*. With these there is formed a shelf-like plate *l''* which is braced to the upper part of the bracket by the web *l''*. The cylinders of the engines at F rest upon the bracket plate *l''*. The engine cylinders are cast with the rearward extending arms and webs at M, which at their rear ends are bolted to the crossbar secured to 100 the front ends of the side bars of the frame J. The rear ends of these bars M have bearings in which the crank shaft is fitted.

N indicates a supplemental central bracket. It has a concave saddle *n* fitting 105 the underside of the boiler, and at the bottom is bolted to the engine castings.

The various minor parts of the engine, proper, need not be here described in detail. They are shown and described in Patents 110

Nos. 842,589 and 842,840, to William N. Springer, dated January 29, 1907, and reference can be made thereto for a full understanding of the devices for governing the engine, and the means for transmitting power from the crank shaft to the ground wheels, the means for changing the speed, the ducts for the live steam and for the exhaust, the valve gear, &c. The front wheels 10 are in this construction supported directly from the forwardly extending part A' of the boiler shell.

O is a bracket secured to the sides of the boiler and extending downward therefrom 15 to support the axle and the carrier for the front wheels.

O' are brace rods rigidly secured to the bottom part o of this bracket and extending backward and upward and bolted to the 20 saddle part l of the bracket standard L. The axle of the front wheels E is secured to a yoke P having a stem or arm p which extends back to and beyond a nut Q to which the arm is pivoted, the arm being forked or 25 so made as to lie partly above and partly below the nut. The nut engages with a threaded shaft R which is mounted in the lower ends of the legs l' of the bracket standard L in the bearings r.

30 S is the steering shaft running from the wheel s at the engineer's platform down to the bevel gear at T which drives spur gearing U, one of the spur wheels being mounted on the threaded shaft R. The arm p 35 is as shown at p' extended behind the screw shaft R and its rear end passes through a keeper or guide at p².

The details of the devices for mounting and steering the front wheels E and their 40 axle are also preferably similar to those shown in the aforesaid Patents, Nos. 842,589 and 842,840, to W. N. Springer, though there can be modification in respect to these as desired.

45 The engines as will be seen are so arranged that the strains exerted by them are transferred to the short rear frame J, the bracket L serving merely as a vertical carrier for the cylinder ends of the engines.

50 The webs or arms M being firmly connected to the cross bars of the main frame serve to transmit the longitudinal strains thereto.

A great part of the weight incident to the 55 heavy wrought beam frame of undermount ed engines as heretofore constructed is dispensed with without sacrificing any of the necessary strength or rigidity of the structure. Moreover, as the side bars of the frame are dispensed with along the front

60 part of the engine ample room is left directly below the boiler in which the steering wheels E can be turned sharply so that an engine having its parts constructed and related as above shown, can be steered with 65 very "short turns". The engines, proper,

being in horizontal planes considerably below the boiler, there is ample space above wherein can be placed the governor mechanism indicated as an entirety by W.

The bracket N serves to combine together 70 the rear ends of the engine frames and to brace them properly in relation to the boiler as well as to support some of the moving parts of the mechanism such as the governor gear.

75 What I claim is:

1. In a traction engine, the combination of the boiler, the rear driving wheels and axle therefor, the main frame below the boiler and supported by the said axle, the 80 crank shaft mounted on the front end of said main frame, the gearing and shafting interposed between the crank shaft and the drive wheels, the engine frames extending forward from the crank shaft and mounted 85 at their rear ends on the said main frame, the downward extending bracket secured to the bottom of the boiler and vertically supporting the front ends of the engine frames independently of the main frame, the front 90 ground wheels and means for supporting the front end of the engine on the said front ground wheels independently of the aforesaid main frame, substantially as set forth.

2. In a traction engine, the combination 95 of the boiler, the drive wheels, the main frame below the boiler connected to the drive wheels, the crank shaft mounted on the forward end of said main frame, the shafting and gearing interposed between the 100 crank shaft and the ground wheels and supported on the said main frame, the engine frames below the boiler, the bracket independent of the aforesaid frame for vertically sustaining the cylinder ends of the engine frames, the bracket independent of the said frame for vertically sustaining the shaft ends of the engine frames, the front supporting wheels for the engine, and steering devices for the said wheels supported 105 on one of the aforesaid brackets, substantially as set forth.

3. In a traction engine, the combination of the boiler, the drive wheels, the crank shaft mounted on the forward end of the 11 main frame, the shafting and gearing interposed between the crank shaft and the ground wheels and supported on the main frame, the engine frames below the boiler, the bracket independent of the aforesaid main frame for vertically sustaining the cylinder ends of the engine frames, the bracket independent of the aforesaid main frame for vertically sustaining the shaft ends of the engine frames, the front ground wheels, and means for supporting the front end of the engine on the said front ground wheels independently of the aforesaid main frame, substantially as set forth.

4. In a traction engine, the combination

- of the boiler, the driving wheels and axle therefor, the main frame below the boiler and supported by said axle, the crank shaft mounted on the front end of said main frame, the gearing and shafting interposed between the crank shaft and the drive wheels, the engine frames extending forward from the crank shaft and mounted at their rear ends on the said main frame, the downward extending bracket secured to the bottom of the boiler and vertically supporting the front ends of the engine frames independently of the main frame, the front ground wheels, means for supporting the front end of the engine on the said front ground wheels independently of the afore-said main frame, and steering devices for the said front wheels supported on the afore-said bracket.
5. In a traction engine, the combination of the horizontal longitudinal boiler, the rear traction wheels supporting the rear end of the boiler, the front dirigible wheels directly supporting the front end of the boiler, the engines supported at their front ends directly from the boiler independently of
- 10
- 15
- 20
- 25

the front wheels, the gearing and shafting between the engines and the traction wheels, and the rigid longitudinal tension and compression connections supplemental to the boiler between the rear wheels and the engines.

6. In a traction engine, the combination of the horizontal longitudinal boiler, the rear traction wheels supporting the rear end of the boiler, the front dirigible wheels directly supporting the front end of the boiler, the engines supported at their front ends directly from the boiler independently of the front wheels, the gearing and shafting between the engines and the traction wheels supported independently of the boiler, and the rigid longitudinal tension and compression connections supplemental to the boiler between the rear wheels and the engine.

In testimony whereof I affix my signature, in presence of two witnesses.

JOHN B. BARTHOLOMEW.
